EXEMPLARY CLAIM

5. An antenna horn for a radar-controlled device comprising a streamlined body having surfaces defining an aperture extending through said body, a composite wave guide disposed in the aperture in said body, said composite wave guide having a straight section and a curved section with an end portion of each section secured together in coaxial alignment, means in one of said sections for modifying electro-magnetic waves passing therethrough, said surfaces of said body being shaped to support one end of the composite wave guide against lateral movement, and means for securing the other end of said composite wave guide to said body against movement in any direction.

WAVE GUIDE ANTENNA HORN

This invention relates to wave guide antenna horns for high velocity radar controlled devices and more particularly to antenna horns having wave guides with filters therein.

An object of the present invention is to provide an antenna horn having a sectional wave guide to facilitate the fabrication thereof.

Another object of this invention is to provide an antenna horn having a composite wave guide with a component thereof comprising a filter for passing a predetermined signal, and to a method of making same.

With these and other objects in view, the invention contemplates casting a metal antenna horn body having a streamlined contour, a flat base face engageable with a device to which it is to be attached, and a tapering aperture therethrough which is disposed obliquely relative to the base face for receiving a composite wave guide therein. The composite wave guide comprises a straight tubular section for receiving signals and a bent tubular elbow section bonded thereto for changing the direction of the signals, the straight section having a plurality of centrally apertured discs bonded to the interior thereof in a predetermined axially spaced relation to each other to form a filter for passing a selected signal, and the elbow section having a flanged positioning sleeve telescoped over and bonded to one end thereof. The elbow end of the composite wave guide with the flanged sleeve thereon is placed in a conforming aperture in an annular mounting flange, and the horn body is telescoped over the wave guide into engagement with the positioning sleeve and the mounting flange, after which the mounting flange is secured to the horn body to securely clamp the wave guide to the horn body in a predetermined assembled relation thereto.

Other features and advantages of the invention will become apparent by reference to the following detailed description thereof and the accompanying drawings, in which

FIG. 1 is a top view of the antenna horn;

FIG. 2 is a side view of the antenna horn with a portion thereof shown in section showing the composite wave guide positioned therein;

FIG. 3 is a fragmentary bottom view of the antenna horn;

FIG. 4 is an end view of the antenna horn;

FIG. 5 is an enlarged vertical sectional view of the composite wave guide of the antenna horn with portions of the antenna horn shown in dotted lines;

FIG. 6 is a longitudinal sectional view of the filter component of the composite wave guide; and

FIG. 7 is an end view of the filter component shown in FIG. 6.

Referring to the drawings, the antenna horn 10 comprises a cast metal horn body 12 which has a substantially flat base face 14, a streamlined outer surface 16 starting from a forward pointed end 18, and a transversely and rearwardly directed aperture 20 therethrough which intersects and is disposed obliquely to the base face 14 for receiving a composite wave guide 22 therein. The aperture 20 tapers from an enlarged end 23 at the base face to a predetermined size at the small end 24 to provide clearance for free movement of the wave guide 22 thereinto and to provide an annular surface at the small end of the aperture 20 for en-

gaging and firmly supporting one end of the wave guide in fixed relation to the horn body.

The wave guide 22, which is made from metal tubing having a uniform inner diameter, comprises a straight section 26 (FIGS. 5 and 6) and a curved elbow section 28. One end of the straight section 26 is externally rabbeted at 30 (FIG. 5) and one end of the elbow section 28 is internally rabbeted at 31 for telescoping engagement and coaxial alignment with each other.

10 The straight section 26 has a plurality of centrally apertured discs or irises 33, 34, 35 brazed thereto transversely of the axis thereof in parallel and predetermined axially spaced relation to each other to form a filter for passing a selected signal therethrough. Because the wave guide section 26 is straight, the discs 33, 34 and 35 may be brazed thereto in a precise predetermined relation to each other. The elbow section 28 of the wave guide has a curved intermediate portion and a straight end portion 38 over which straight portion a 15 positioning sleeve 39 is telescoped and brazed thereto at 40. A flange 41 on one end of the mounting sleeve has an end face 42 engageable with the base face 14 of the horn body 10 as an aid in locating the composite wave guide 22 in a predetermined precise position on the horn body.

20 After the positioning sleeve 39 has been assembled and brazed to the elbow section 28 of the wave guide, three holes are drilled radially through the sleeve 39 and the end portion 38 of the elbow section in predetermined precisely located positions below the flange 41. Three polarizing pins 43 are then pressed into the holes with the ends of the pins extending into the wave guide a predetermined distance for effecting a predetermined change in the electrical characteristics of the 25 signal passing through the wave guide. Prior to the assembling of the positioning sleeve 39 onto the end portion 38 of the elbow component 28 the end portion 38 is slotted to receive a flat resistor 44. After the positioning sleeve 39 has been assembled and brazed to the elbow section 28 of the wave guide, and after the pins 43 have been pressed into position on the elbow section, the straight filter section 26 is assembled onto the elbow section 28 and brazed thereto at 45 (FIG. 5), and the resistor 44 is then assembled in the slotted end portion 38 of the composite wave guide and secured thereto by a pair of set screws 44a in the sleeve 39.

30 The end portion of the wave guide with the sleeve 39 thereon is then placed in a conforming seat or aperture in an annular mounting bracket or flange 46 which has a flat shoulder 47 for supporting the flange 41 and has an upper face 48 flush with the end face 42 of the sleeve 39. The lower portion of the mounting flange 46 is provided with an annular groove 55 for receiving a choke ring. The horn body 12 is then telescoped over the wave guide 22 into assembled relation therewith as shown in FIG. 2 and with the base face 14 of the horn body in engagement with portions of the flat faces 48 and 42 of the mounting flange 56 and sleeve 39, respectively, and with the sleeve 39 and the end portion 38 of the wave guide extending from the flat face 14 of the horn body in a direction substantially perpendicular thereto. The other end of the wave guide is firmly supported against lateral movement in the small end 24 of the aperture 22 in the horn body 12. Two screws 49 are then driven into aligned apertures 50 and 51 in the mounting flange 46 and the horn body 12 respectively, to secure the mounting flange 46 and the composite

wave guide 22 to the horn body in a predetermined relation thereto.

The mounting flange 46 has a plurality of mounting holes 52 (FIGS. 1 and 3) for receiving fastening screws therein by means of which the antenna horn 10 may be secured to a device with the flat base face 14 of the cast horn body in engagement with the device and the mounting flange 46 seated in a recess therein. If, after testing the assembled wave guide and horn, it has been determined that the pins 43 are not properly positioned, the screws 49 and the mounting flange 46 are removed and the selected pin or pins 43 are forced by a suitable device forwardly or rearwardly as required to reposition the pins in the precise position desired.

From the foregoing description, it will be seen that a sturdy antenna horn with wave guide and filter is provided in which the components are rigidly secured together in precise relation to each other, and that with this design of the antenna horn, a method of fabrication may be practiced wherein the filter forming discs may be precisely located in predetermined positions within the wave guide, the wave guide precisely and securely positioned within the cast horn body, and the polarizing pins readily adjusted to meet critical electrical requirements.

It is to be understood that the above-described arrangements are simply illustrative of the application of the principles of this invention. Numerous other arrangements may be readily devised by those skilled in the art which will embody the principles of the invention and fall within the spirit and scope thereof.

What is claimed is:

1. An antenna horn for a radar controlled device comprising a streamlined body having a substantially flat face and an aperture extending therethrough obliquely from the flat face, a composite tubular wave guide disposed in the aperture in the body and with an end portion projecting from the body in a direction substantially perpendicular to the flat face thereof, said composite wave guide including an elbow component and a straight component, said straight component having a plurality of transversely disposed centrally apertured discs secured therein in predetermined axially spaced relation to each other, said elbow component being curved intermediate its ends and having straight end portions disposed obliquely to each other and with one end bonded to one end of the straight component, and means engageable with the projecting end portion of the composite wave guide for securing it to the body.

2. An antenna horn for a radar controlled device comprising a streamlined body having a substantially flat face and an aperture extending therethrough obliquely to and tapering from the flat face, a tubular wave guide having relatively long straight first end portion and a curved intermediate portion disposed within the aperture in the body and having a relatively short straight second end portion projecting from the body substantially perpendicular to the flat face, said body at the small end of the tapering aperture engaging the first end portion of the wave guide and securely supporting it against lateral movement, an annular member telescoped over and bonded to the projecting end of the wave guide and engaging the flat face of the body for locating the second end of the wave guide in a predetermined position on the horn body, said annular member and said projecting end of the wave guide having predetermined common radially disposed apertures

therein, polarizing pins frictionally and adjustably supported in the said apertures and projecting into the wave guide, an apertured mounting flange telescoped over the end of the annular member and the projecting end portion of the wave guide and engaging the flat face of the horn body for holding the wave guide in position on the horn body, and means for fastening the mounting flange to the horn body to secure the wave guide to the horn body.

3. An antenna horn for a radar controlled device comprising a streamlined body having a substantially flat face and an aperture extending therethrough obliquely to and tapering from the flat face, a composite tubular wave guide disposed in the aperture in the body and with an end portion firmly supported by the body in the end of the said aperture and with the other end portion of the wave guide projecting from the body substantially perpendicular to the flat face thereof, said composite wave guide including an elbow component and a straight component, said straight component having a plurality of transversely disposed centrally apertured discs secured therein in predetermined axially spaced relation to each other, said elbow component being curved intermediate its ends and having straight end portions disposed obliquely to each other and with one end thereof bonded to one end of the straight component and with the other end thereof forming the projecting end of the wave guide, a sleeve telescoped over and secured to the projecting end of the wave guide for engaging the flat face of the body, a plurality of pins, said telescoped portions of the sleeve and the wave guide having apertures for adjustably supporting the pins with portions thereof disposed radially within the wave guide, an apertured mounting member telescoped over the sleeve and engaging the flat face of the body for supporting the projecting end of the wave guide, and means for removably securing the mounting member to the body and against the flat face to secure the composite wave guide to the body.

4. An antenna horn for a radar controlled device comprising a streamlined body having a substantially flat face and an aperture extending therethrough obliquely to and tapering from the flat face, a composite tubular wave guide disposed in the aperture in the body and with an end portion firmly supported by the body in the small end of the tapered aperture and with the other end of the wave guide projecting from the body substantially perpendicular to the flat face thereof, said composite wave guide including a tubular elbow component and a tubular straight component with rabbeted ends telescoped and bonded together in coaxial alignment, said straight component having a plurality of transversely disposed centrally apertured discs secured therein in predetermined axially spaced relation to each other, said elbow component being curved intermediate its ends and having straight end portions disposed obliquely to each other and with one of the ends thereof forming the said projecting end portion of the wave guide, a sleeve secured to the projecting end of the wave guide and having a flange engaging the flat face of the body, an apertured mounting member telescoped over the sleeve and engaging the flat face of the body for supporting the projecting end of the wave guide, and means for fastening the mounting member to the body for securing the composite wave guide to the body.

5. An antenna horn for a radar-controlled device comprising a streamlined body having surfaces defining an aperture extending through said body, a composite wave guide disposed in the aperture in said body, said composite wave guide having a straight section and a curved section with an end portion of each section secured together in coaxial alignment, means in one of said sections for modifying electro-magnetic waves passing therethrough, said surfaces of said body being shaped to support one end of the composite wave guide against lateral movement, therethrough, and means for securing the other end of said composite wave guide to said body against movement in any direction.

6. An antenna horn for a radar-controlled device comprising a streamlined body having a substantially flat face and an aperture extending therethrough transversely of said flat face, a composite wave guide extending through said body in said aperture, said wave guide having a straight section and a curved section with an end portion of each section bonded together in coaxial alignment, means in said straight section for modifying electro-magnetic waves passing there-

through, means in said curved section for modifying electro-magnetic waves passing therethrough, and means for securing the composite wave guide to said body.

5 7. An antenna horn for a radar-controlled device comprising a streamlined body having a face adapted to be juxtaposed with said device and having surfaces defining an aperture extending through the body transversely of said face, a composite wave guide extending 10 through said body in said aperture, said composite wave guide having a straight section and a curved section with an end portion of each section bonded to each other in coaxial alignment, means in said straight section for modifying electro-magnetic waves passing therethrough, means in said curved section for modifying electro-magnetic waves passing therethrough, said surfaces of the body engaging the straight section of the wave guide to support one end of said composite wave guide, and means engaging the curved section adjacent 20 said face of the body for securing the composite wave guide to said body.
